SHOULDER BAG

Maxwell B. Chernoff, Little Silver, N.J., assignor to Dart Industries Inc., Los Angeles, Calif.

Filed Mar. 5, 1974, Ser. No. 448,446

Term of patent 14 years

Int. Cl. D3—02

U.S. Cl. D87—3 C

FIG. 1

FIG. 2

FIG. 3

FIG. 4

FIG. 1 is a perspective view of a shoulder bag embodying my new design;

FIG. 2 is a rear view of the bag shown in FIG. 1;

FIG. 3 is a top view thereof; and

FIG. 4 is a bottom view thereof.

I claim:

The ornamental design for a shoulder bag, substantially as shown.
